MASS SPECTROMETER APPARATUS

Alfred O. C. Nier, Minneapolis, Minn., assignor to
 Regents of the University of Minnesota, Minneapolis, Minn., a corporation of Minnesota

Application April 2, 1951, Serial No. 218,712

13 Claims. (Cl. 250—41.9)

1

This invention relates to improved mass spectrometers and particularly to improvements in a non-fractionating gas sample supply mechanism for use in mass spectrometer analysers and the like where the actual weight of samples handled by the apparatus is exceedingly small.

This application is a continuation of my pending application, Ser. No. 783,431, filed October 31, 1947.

In general it may be stated that a mass spectrometer consists of a highly evacuated vessel having an electron source that is utilized for charging atoms or molecules so that they exist within the vessel as ions. The evacuated vessel is so constructed that it presents a path of travel for the ions, which are accelerated by a suitable potential gradient so that they travel along said path and collectively constitute an electric current. The path of travel includes a certain section which is through a strong magnetic field which serves to deflect the moving ions to a degree depending upon their masses and the strength of the magnetic field whereupon after further travel they are collected and the ion current which they represent is measured or otherwise utilized.

In instruments of this character, the sample which is in the gas phase is introduced into the mass spectrometer tube in the region of the filament thereof, whereupon the molecules or atoms of the sample (which may be a mixture of many materials) become ionized. The components of the sample are separated or "analyzed" by the functioning of the mass spectrometer and an indication (or indications) provided by which the existence of the proportion of various components of the sample can be determined.

The proper functioning of the mass spectrometer in analyzing samples requires, first, that the sample be introduced into the mass spectrometer in very small amounts, preferably continuously; and second, that the act or apparatus used for introducing the sample in and of itself should not fractionate the sample, for the composition of the sample must have a known relation to the same composition when it is inside the mass spectrometer tube. In addition where sampling is done on a continuous basis the sampling system should not introduce any undue delay between the time the sample is taken and the time it is analyzed.

It is therefore an object of the present invention to provide an improved mass spectrometer gas analyzing device and particularly to provide a mass spectrometer wherein the gas sample is

2

introduced in minute amounts and without fractionating the sample in so doing, and without undue delay.

It is also an object of this invention to provide an improved, non-fractionating gas sampling device for use in conjunction with gas analyzing mass spectrometers of simple, economical construction which is easily adjustable and convenient to service.

It is also an object of this invention to provide a gas sample supply for a mass spectrometer which is adapted for accurate control of minute quantities of gas which are admitted to the system.

Other and further objects of this invention are those inherent in the apparatus herein illustrated, described and claimed.

The invention is illustrated with reference to the drawings in which:

20 Figure 1 is a side elevational view of mass spectrometer embodying the instant invention;

Figure 2 is a somewhat enlarged, partially schematic side elevational view of portions of the apparatus shown separated from the frame of the

25 machine in order to show the details more clearly;

Figure 3 is a plan view of the gas supply apparatus forming a component of the apparatus of the instant invention shown in Figure 1, Figure 3 being illustrated partially in section, the section being along the line in the direction of arrows 3—3 of Figure 4;

Figure 4 is a side sectional view of the component shown in Figure 3, taken along the line and in the direction of the arrows 4—4 of Figure 3;

Figure 5 is an end sectional view of the component shown in Figure 3, taken along the line and in the direction of arrows 5—5 of Figure 3;

Figure 6 is an enlarged fragmentary sectional view taken along the line and in the direction of arrows 6—6 of Figure 3.

Referring to the drawings, Figure 1 particularly, the apparatus comprises a main frame which may conveniently be composed of angle irons. The frame has a floor angle 10, posts 11 and 12 and intermediate frame member 13 and top frame member 14. Upon the intermediate frame member there is mounted the magnet assembly generally designated 15 which may be either an electromagnet as illustrated or a permanent magnet. In any event the magnet 15 is an exceedingly heavy part of the apparatus and is mounted directly upon the frame members 13 in fixed position on the frame. The magnet 15 as

illustrated has a core 16 and a winding 18. The core has an air gap which is defined by pole pieces having the configuration shown by the dotted line 19. The core, which is U-shaped in plan view, has an interior opening 20 between the legs of the U and between the coil and the rear core connection 21 through which some of the supporting bracket structure passes, as hereinafter defined. The entire core structure is assembled by means of the heavy bolts 22 and is fastened to the frame by fastening devices so as to be fixed on the frame.

Upon the upper surface of the core there is provided a bracket 24 of open box formation having upwardly extending supports 25. The bracket has a cap portion 26 which is provided with matching downwardly extending legs 28 which meet the upwardly extending supports 25 at the separating line 29-29. The portions 25-25 and 28-28 are provided with a circular aperture 30, not shown, through which the tubular connection 31 of the evacuable system is adapted to pass. The two portions 24 and 26 of the bracket are held in clamping relation by a pair of studs 32 only one of which is shown which are tapped into the upper surface of the magnet core 21. The studs are provided with nuts at 33 which when pulled down exert a clamping pressure upon the tubular connection 31. By loosening the nuts 33 the tubular connection may be moved back and forth in the direction of the double arrow 34 and to a limited extent the bracket 24-26 may be rotated so as to exert a slight rotary motion on the evacuable assembly for adjustment as hereinafter described. In addition, by inserting or removing shims between the lower surface of the bracket 24 and the upper surface of the core 21 at the level 35, it is possible to raise and lower the evacuable assembly slight amounts for adjustment purposes.

The evacuable assembly consists of a tubular cross connection 31 which is provided at its right end, as shown in the drawings, with a downwardly extending branch 37 which terminates in the flange 38. The under side of the flange 38 is ground so as to provide a spherical seat at 39 which fits the spherical connection 40 of the glass mercury diffusion pump apparatus shown generally opposite the bracket 41. The diffusion pump includes a vertical outlet tube 42 which leads downwardly into the moisture freezing trap bulb 43 to which it is sealed at 44. From the trap 43 there is a side arm 45 extending to the mercury vapor pump section at 46. The mercury vapor pump is provided from the mercury boiler 47 which is heated by an electrical heating element 48, the vaporized mercury passing upwardly through the tube 49 and thence to the pumping section 46 where the pumping action takes place and the mercury is incidentally condensed to liquid form which returns from the bulb 50 and thence via pipe 51 to the mercury boiler 47. The gases and vapors withdrawn by the mercury pump are delivered at the outlet tube 52 which is connected by a flexible rubber hose or other flexible lead 53 to the pipe 54, Figure 1, which leads through the control valve 55 and line 56, flexible connection 58 to the fore-pump 60 which can be of any suitable variety and driven by motor 61 mounted upon the bed plate 62 that is in turn mounted upon the main frame members 10. Valve 64 provides for breaking the vacuum when desired and valve 55 for closing off line 54.

The seal of the spherical connection between the glass ball 40 and the metallic spherical seat 39 is made by coating the members with ordinary red sealing wax which is heated and the two parts pushed firmly together, after which they are permitted to cool. A cooling coil 65 is soldered to the metallic flange 38 for cooling the flange during gassing out operations, hereinafter described, so as to prevent damage to the seal.

At its left end, as shown in the drawings, Figures 1 and 2, the tubular cross connection 31 is joined to the mass spectrometer tube which includes an upper straight tubular section 66 of circular cross section which is reduced slightly at 67 and joined to the segmental curved tubular section 68 which is in turn connected to the straight tubular section 69 terminated in the ion collector 70. The curved segmental portion 68 is flattened in cross section so as efficiently to occupy the space between the pole faces 19. At the upper end of the straight section 66 there is a flange 72 which is arranged to be cooled by the soldered-on cooling pipe 73. To the flange 70 there is connected a mating flange 74 which is held by suitable clamping bolts. Flange 74 is likewise arranged to be cooled by the soldered-on cooling coil 75. Upon the flange 74 there is mounted the entire ion source assembly shown opposite the bracket 76 which is suitably mounted and connected to the incoming leads 77 that are in turn connected to the separable coupling 97. To the flange 74 there is also connected the inlet pipe 126 which extends, as illustrated in Figure 2, into the interior of the ion source delivering into the chamber 79 containing the electron emitter filament 80. The sample undergoing analysis is introduced via tube 126 and is thus delivered into the region of the electron emitting filament 80 where due to electron emission the sample becomes ionized. The ionized sample is withdrawn from the chamber 79 through the slit 81 by a system of potential gradient plates 82. The plates 82 serve not only to accelerate the ionized sample, but also to focus it in a beam of ions which passes in the direction of the dotted line 83, thence downwardly along the tube portion 66 until it enters into the strong magnetic field defined by the pole pieces 19. The ionized particles of the sample behave as an electric current and are deflected by the magnetic field along the curved path 84 in an amount depending upon the strength of the magnetic field, the velocity of the particles and their mass. The velocity is maintained constant or as nearly constant as possible, and since the same magnetic field is common to all of the ionized particles, the amount of deflection occasioned by their passage through the strong magnetic field is, therefore, dependent upon the mass of the particles. Consequently, the stream of ionized particles after having passed through the magnetic field emerges as a spectrum 85, the lighter ionized particles being deflected most, as exemplified by the dotted line 86, and heavier particles deflected least, as exemplified by the dotted line 87. The particles are caught upon separate ion collecting plates 88 and 89 of the ion collector mechanism 70 where they give up their charges to the plates. The charges upon plates 88 and 89 constitute the effective signal and these are communicated by leads 90 and 91 which pass out through the glass squash 92 and thence through the flexible (Sylphon bellows) housing 93 to separate pre-amplifiers in the common pre-amplifier chamber 94 which is cushion-mounted

by means of the mounting 95 that rests upon the bracket 96 attached to the frame members 11.

Referring to Figures 3-6, the mechanism by which the gas sample is introduced into the mass spectrometer mechanism which is illustrated in those figures and is shown opposite brackets 99 in Figure 1 includes a base plate 120 which may be mounted in any convenient plane such as horizontally or vertically by means of fastenings placed through openings 121. Adjacent one end of the plate there is a block 122 which is preferably removably attached by screws 123-123. The block 122 serves to support inlet tube 124 which is connected at its exterior end 125 to the sample source which is at relatively high pressure, which is customarily in the range of 10⁻⁶ to 200 mm. of mercury pressure. Block 122 also serves to support the outlet tube 126 which is connected at its exterior end 127 to the inlet tube of the mass spectrometer. Tube 126 is accordingly maintained at the low pressure maintained in the mass spectrometer tube, which is customarily held in the range of 10⁻⁶ to 10⁻⁴ mm. of mercury pressure.

Both tube 124 which is connected to the gas sample supply and tube 126 which is connected to the mass spectrometer as shown in Figures 1 and 2 are fastened to the block by soldering or brazing, shown at 128 and 129. The inner end 130 of tube 132 which is connected to tube 124 by a metal adapter 134 between the two tubes and the adapter being made gas-tight as by soldering.

The capillary tube 132 then continues through a long course of travel, length L, including turns 135 and goes through the constriction generally designated 136 and then continues through a short travel S from the constriction 136 to the end 137 of tube 136 to which it is attached in gas-tight relation by means of an adapter 138 to which both tubes are soldered. The entire tube 132 and constriction 136 is covered by housing cup 149 which is held in place by a single cap screw 142, which is of the recessed head (Allen) type and is threaded into base 120. The cup is notched out at 148 and 149 to permit entry of tubes 124 and 126.

The constriction 136 of capillary tube 132 is constructed by passing the tube 132 under a simple clamp bar 143 that is arranged to be drawn down by the recessed head cap screws 144 and 145 that pass through holes in bar 143 and are threaded into base 120. The lower edges of bar 143 are rounded off at 146 and 148 so as not to present a sharp corner to the tube 142 which is engaged and flattened as the bar 143 is drawn down. The pressure of clamp bar 143 on capillary tube 132 flattens the tube throughout the area 147 and restricts its cross-sectional area to any desired degree thus throttling the gas sample. By loosening screws 144 and 145 the pressure on clamp bar 143 may be relieved and, due to the resiliency of the tube, it tends to spring open and increase the cross-sectional area at the restriction. This permits ready adjustment of the constriction of the capillary tube.

In a typical installation in accordance with this invention the total length (L plus S) of capillary tube was 20 inches, the tube being of seamless, hard drawn copper tubing having an inside diameter of .003 inch. The constriction was in this installation about one inch from tube 126; length S was, therefore, approximately one inch.

The purpose of the long length L of capillary tubing is to prevent back diffusion of gas, and hence fractionation at the constriction where a

combination of viscous and molecular flow takes place. In accordance with this invention the capillary diameter and length L are chosen so that the mass flow velocity of the sample in the capillary tube toward the constriction 147 will be greater than the back diffusion velocity of any component of the gas mixture through the constriction 147. Hence, the gas sample entering tube 126 leading to the spectrometer will be representative of that in the supply manifold tube 124 from container 100. By thus choosing the capillary tube length L and its inside diameter so as to insure having a mass flow velocity of the gas sample (through the capillary tube portion L) which is greater than the back diffusion velocity of any component through the constriction 147, it is possible to insure against fractionation of the sample at the constriction even when the gas sample is a complex mixture consisting of constituents of widely differing viscosity and widely varying molecular weights.

In general it may be stated that in accordance with my discovery, the capillary tube should have an inside diameter of not less than .002 inch and preferably not more than .012 inch. The length L for such tube should be not substantially less than 15 inches and I prefer to use a capillary tube not less than 20 inches for the length L, thus a length L in the range of 20 to 100 inches gives good results, the length S being as short as practically possible. There is no fixed maximum for length L but L should not be appreciably less than 15 inches. Even greater lengths than 100 inches may be used where the time delay factor is not a disadvantage. The length S should be kept short enough so that there is little pressure drop through this portion of the capillary tube so as not to cause the gases flowing therethrough to have a viscous flow. The length S should preferably be not more than two to three inches, and in most installations can be kept to a length of about 1 inch without undue mechanical difficulty.

Thus, an excellent gas sampling orifice was composed of capillary tube having an inside diameter of .007 inch, a length S of 1 inch and a length L of approximately 40 inches and constricted as shown in Figures 3 and 6. Another excellent gas sampling orifice utilized a capillary tube having an inside diameter of .010 inch, a length S of approximately 1 inch and a length L of approximately 20 inches and constricted as shown in Figures 3 and 6. For most installations I prefer that the capillary tube have an inside diameter not smaller than .004 inch and a practical lower limit of the tube is .002 inch.

Best results are obtained if the pressure in the sample tube 124 is not less than 10 cm. of mercury. The pressure in the sample tube can be increased without difficulty. The constriction caused by the squeeze imposed on the capillary tube by the bar 143 limits the flow through the capillary tube at the constriction to approximately 1 cubic centimeter of gas in 24 hours calculated at normal pressure and temperature. The squeeze can be adjusted more or less so as to maintain the mass spectrometer in the correct pressure operating range, as hereinbefore stated. Most mass spectrometers have an operating pressure of about 10⁻⁶ mm. of mercury and an operating range of from 10⁻⁴ to 10⁻⁷ mm. of mercury. The range that is customarily held is from 10⁻⁴ to 10⁻⁶ mm. of mercury, as previously stated herein. If the gas in the mass spectrometer is insufficient (i. e. the pressure decreases) the mass spectrometer becomes less sensitive.

If the pressure in the mass spectrometer increases, the ions that are generated tend to scatter and the operation of the mass spectrometer becomes erratic. By adjusting the squeeze on the capillary tube 132, as provided by the squeezing bar 136, it is possible to regulate the constriction so that just the proper amount of gas rushes through the constriction so as to maintain the pressure within the mass spectrometer in the appropriate range for best action.

The diffusion coefficients and viscosity coefficients of various gases do not vary a great deal so that one setting of the constriction bar 136 will be satisfactory for most gases ordinarily analyzed.

If the length L of the capillary tube is increased, the operator may permissibly use lower pressure in the gas supply tube 124, but increased length L of the capillary tube offers a disadvantage in that a greater time is required to pull a given unit quantity of gas through the increased length of capillary tube. Thus, where the sampling orifice forms a part of a mass spectrometer system for continuous analysis of gas, there would be a time lag in the indication of the instrument, and the instrument would always read what the gas composition had been a given time period previously. This is because the amount of gas filling the capillary tube has to be drawn therethrough. According, from this standpoint it is desirable to select the length L as short as possible, so as to decrease this time lag. Where the time lag factor is no disadvantage, an increase in length offers no objection.

It is desirable to make the inside diameter of the capillary tube small so that the gas through it will flow more rapidly (with a mass flow velocity), but the inside diameter should not be so small as to produce a molecular flow. Thus, if exceedingly small capillary tubes, as tubes below .002 inch I. D. is used, such tubes will produce a molecular flow with consequent fractionation at most sample pressures.

The back diffusion of gases through the constriction of the tube under the squeeze bar 136 can be overcome by keeping the flow through the constriction fast enough and by utilizing a tube length L not substantially less than 15 inches long and preferably 20 or more inches long. The longer tube length L that is provided, allows the gases on the sample side of the constriction to diffuse back far enough so that the concentration of the back-diffused gases per unit of volume remains negligibly small.

The lighter gases go through the constriction faster than the heavier gases, and the heavier gases accordingly build up on the sample side of the constriction. Difficulty due to increase of such concentration is eliminated by utilizing a tube having an inside diameter in the range of from about .002 inch to .012 inch and a length L not substantially less than 15 inches and preferably 20 or more inches, the length S being meanwhile kept relatively much shorter, viz. not substantially more than 3 inches and preferably about 1 inch or less.

In prior instruments used for laboratory analysis of complex gas mixtures, the problem was solved by having the sample at very low pressures so as to insure that true molecular flow conditions existed. By using the apparatus of the present invention, one is not limited to the use of gas samples at low pressures. The apparatus is thus adapted for continuous analysis of gases

from any source of gas connected to tube 124 which may be under positive or negative gauge pressure, so long as the source pressure is positive in respect to that in the tube 126.

Various adjuncts of the mass spectrometer tube include the framework 101 which is mounted upon the tubular cross connection 31, as shown in Figure 1. Element 101 has been eliminated in Figure 2 for purposes of clarity. The framework 101 which is suitably adjustable upon tube 31 serves in turn adjustably to support the frame 102 which is of horse shoe configuration in bracing the tube 66, the horse shoe frame 102 carries permanent focusing magnets. A further focusing magnet assembly is illustrated at 103, this being carried upon the frame 104 which likewise is adjustably mounted upon the tube 69. At the right end of the tubular connection 31 there is a branch 105 which extends to the Phillips gauge mechanism 106 which, per se, forms no part of the present invention. The Phillips gauge mechanism is a very sensitive pressure measuring device operating on the electron bombardment principle.

Extending downwardly from the tubular cross connection 31 there is an interior support brace rod 107 which is clamped to the tubular connection by means of the clamping bracket 108. The brace rod 107 extends down between the spaced legs of the large magnet 15 and is connected at its lower end to the mercury diffusion pump mechanism 41 so as to support it.

Upon the rear of the main frame there is a vertical bracket rod 110 upon which there is adjustably mounted the side arm bracket 111 supporting the plate 112. The plate 112 serves to carry an open top Dewar flask 113 into which the bulb 43 of the freezing trap in the mercury diffusion pump is adapted to be immersed. The brace 111 may be loosened by unscrewing the wing nut 114 so as to permit lowering of the Dewar flask 113 for replenishing the liquid air supply therein and by the same adjustment the Dewar flask may be positioned so that the bulb 43 is submerged into the flask and yet not in contact with it.

For the most part the mass spectrometer tube is composed of an alloy such as Inconel (trademark) or other suitable high temperature alloy. Thus, the tubular cross connections 31 and the ion path tube consisting of branches 66, 67, 68 and 69, the flanges 72 and 74 and the metallic portions of the ion collector mechanism 70, as well as the branch 37 leading to the mercury diffusion pump and the branch 105 leading to the Phillips gauge are all made of such alloy. In placing the apparatus in operation it is necessary to degas it by heating these metallic parts, and yet certain areas of the apparatus must not be heated beyond prescribed temperatures, otherwise gaskets, etc. will be deteriorated. In order to provide local cooling, cooling water tubes are soldered on at the prescribed places. Thus, a cooling water tube 65 is soldered onto the flange 33, thus chilling it while the adjacent portions are heated, thus preventing the softening of the red sealing wax by which the joint 39-40 is sealed. Cooling water tubes are also soldered onto the flanges 72 and 74 as indicated at 73 and 75. All the cooling water tubes are connected in series or parallel, as desired. Other cooling water tubes 117 and 118 extend down to the mercury diffusion pump connections 119 and 120, respectively.

It will be observed that in the described struc-

ture the entire mass spectrometer tube, including the mercury diffusion pump for evacuating the spectrometer tube, and all adjuncts of the tube are mounted upon evacuable assembly which is in turn carried on the bracket 24-26. Thus, the cross connection 31 of the evacuable assembly has at its right end the downwardly extending branch which consists of the mercury diffusion pump which hangs as a pendulous mass at the right end, being partly supported through the connection 37 and partly through the brace rod 107. At the left end of the tube 31, as shown in the drawings, there is the ion path defined by the tubes 66-69 having at the upper end the ion source assembly 76 and its appropriate connections and adjuncts and at the lower end the ion collector 70. In addition, all the adjuncts, including the focusing magnet assemblies 102, 103 and the Phillips gauge 106 are mounted upon the evacuable assembly and are supported through it upon the bracket 24-26. Consequently, by loosening the bracket 24-26 it is possible to shift the entire evacuable assembly with reference to the magnet 15 and thus obtain precision adjustment of the ion beam 83 with reference to the pole pieces 19. It will be noted that the pole pieces 19 define a segment of sixty degrees and that the ion source 76 and ion collector 70 are aligned as indicated at 121. The focusing and adjustment are critical, and for best results may in the present apparatus be made by a single simple adjustment, whereas heretofore the adjustment has had to be made by movement of the heavy magnet 15, a cumbersome adjustment at best.

In the illustrated form of the invention the preamplifier 94 is mounted on the frame 11 and connected to the mass spectrometer tube at the flexible connection 93 which permits movement of the tube relative to the preamplifier case 94. If desired, however, the preamplifier may be constructed of light weight materials and hung on the lower end of the tube 69 adjacent the ion collector plates. Likewise, if desired, the fore-pump 60 and its drive motor may be hung from the brace rod 107 which may also support the plate 112 for supporting the Dewar flask 113 of the freezing trap.

If the mass spectrometer tube is made movable and the high vacuum pump stationary so as to allow the mass spectrometer tube to be moved without moving the pump, this involves the provision of a flexible high vacuum connection between the two elements. While connections of this kind can be made by employing Sylphon bellows, they are never completely satisfactory. A Sylphon bellows has a great deal of surface area and hence is difficult to gas out satisfactorily. Moreover, they are subject to vacuum leaks.

As many apparently widely different embodiments of this invention may be made without departing from the spirit and scope thereof, it is to be understood that I do not limit myself to the specific embodiments herein except as defined by the appended claims.

What I claim is:

1. In a mass spectrometer having a gas sample inlet the improvement comprising a non-fractionating gas sampling device comprising a gas sample supply tube, a long capillary tube having a gas passage completely therethrough connected to the mass spectrometer gas sample supply tube and to said spectrometer gas sample inlet, a constriction in the capillary tube located relatively

closer to spectrometer gas sample inlet than to the gas sample supply tube, the size of the capillary tube and the degree of constriction thereof being such that the mass flow velocity of gases through the tube is greater than the back diffusion velocity of said gases at said constriction.

5 2. In a mass spectrometer having a gas sample inlet, the improvement comprising a gas sample supply tube, a long capillary tube having one end connected to said supply tube and having the other end of said capillary connected to the gas sample inlet of said mass spectrometer, said capillary tube having a constriction adjacent the gas sample inlet of said mass spectrometer, said capillary tube having an internal diameter of not substantially less than .002" and a length from said constriction to said supply tube not substantially less than 15 inches.

10 3. The apparatus of claim 2 further characterized in that the constriction of the capillary tube is formed by flattening the capillary tube.

15 4. The apparatus of claim 2 further characterized in that said capillary tube is flattened by being clamped between two plates and means is supplied for drawing the plates together to vary the degree of clamping pressure.

20 5. In a mass spectrometer having a gas sample inlet, the improvement comprising a gas sample supply tube, a long capillary tube having one end connected to said supply tube and having the other end of said capillary connected to the gas sample inlet of said mass spectrometer, said tube having an inside diameter in the range of approximately .002 to .012 inch, said capillary tube having a constriction intermediate its ends, the length of said capillary tube from said constriction to said supply tube being not substantially less than 15 inches.

25 6. In a mass spectrometer system having a gas sample inlet, a gas sample enclosure, a long capillary tube connecting said gas sample enclosure to the gas sample inlet of said mass spectrometer, said capillary tube having an inside diameter in the range of approximately .002 to .012 inch, a constriction in said capillary tube adjacent the 30 gas sample inlet of said mass spectrometer, the length of said capillary tube from said constriction to said gas sample enclosure being in the range of about 15 inches to about 100 inches.

35 7. In a mass spectrometer having a gas sample inlet, a gas sample enclosure, a capillary tubular connecting said gas sample enclosure and said gas sample supply inlet of said mass spectrometer tube, said capillary tube having a constriction adjacent said gas sample supply inlet 40 of the mass spectrometer, the length of said capillary tube from said constriction to said gas sample enclosure being approximately 40 inches and the inside diameter of said capillary tube being approximately .007 inch.

45 8. In a mass spectrometer having a gas sample inlet, a gas sample enclosure, a capillary tubular connecting said gas sample enclosure and said gas sample supply inlet of said mass spectrometer tube, said capillary tube having a constriction adjacent said gas sample supply inlet 50 of the mass spectrometer, the length of said capillary tube from said constriction to said gas sample enclosure being approximately 20 inches and the inside diameter of said capillary tube being approximately .003 inch.

55 9. In a mass spectrometer the improvement comprising a non-fractionating gas sampling device comprising supply and outlet tubes each having gas passage ways therethrough, a length 60 of capillary tubing which likewise has a gas pas-

11

sageway therethrough connected to said tube so as to form a continuous gas passageway from the supply tube to the outlet tube for drawing a gas sample from said supply tube to said outlet tube, and means contacting the capillary tube adjacent its point of connection to the outlet tube for applying clamping pressure on the capillary tube for flattening and thereby constricting the capillary tube.

10. The apparatus of claim 9 further characterized in that said means includes a plate along which the capillary tube extends, a clamping bar extending transversely across the capillary and means for drawing the clamping bar toward the plate with the capillary tube between for exerting pressure on the capillary tube to flatten and constrict the opening therethrough.

11. The apparatus of claim 10 further characterized in that the plate also serves as a support for the supply and outlet tubes and that the capillary tube connection between them is coiled by it and the clamping bar are covered by a housing fastened onto the plate.

12. A non-fractionating gas sampling device comprising supply and outlet tube each having a gas passageway therethrough, a length of capillary tubing which likewise has a gas passageway completely therethrough connected to said tubes so as to form a continuous gas passageway from the supply tube to the outlet tube for drawing a

12

gas sample from said supply tube to said outlet tube and means contacting the capillary tube adjacent its point of connection to the outlet tube for applying clamping pressure onto the capillary tube for flattening and thereby constricting the capillary tube, said means including a plate along which the capillary tube extends and a clamping bar extending transversely across the capillary tube and means for drawing the clamping bar toward the plate with the capillary tube therebetween.

13. In a mass spectrometer analyzer the improvement which consists of a non-fractionating gas sampling device comprising supply and outlet tube each having gas passageways therethrough, said outlet tube being connected to said analyzer adjacent the filament region thereof, a length of capillary tubing having a gas passageway completely therethrough connected to said tube so as to form a continuous gas passageway from the supply tube to the outlet tube for drawing a gas sample from said supply tube to said outlet tube, and means contacting the capillary tube adjacent its point of connection to the outlet tube for supplying clamping pressure on the capillary tube for flattening and thereby constricting the capillary tube.
